DEHYDRATOR

Joseph Norman Paquin, Euclid, and Edward P. Bock, Cleveland Heights, Ohio, assignors to The Weatherhead Company, Cleveland, Ohio, a corporation of Ohio

Application November 23, 1945, Serial No. 630,480

3 Claims. (Cl. 210—131)

1

Our invention relates to apparatus for treating fluid streams. It relates, for example, to dehydrators or similar fluid-treating devices, such as are used in mechanical refrigeration systems, and in other situations where it is important to remove moisture or other undesirable materials from fluids, or for otherwise chemically treating fluids flowing in a stream.

An object of the invention is to provide an improved, sturdy, durable, inexpensive dehydrator or dryer and a method of making it.

It is among the objects of the invention to provide a compact, light-weight, and efficient dryer and strainer, or similar device which is leak-proof and safe, and which can be manufactured economically and rapidly.

Another object is to provide a device which also acts as a filter, and in which means are provided for preventing the moisture-absorbing material from being carried along with the fluid passing through the dryer.

Although the invention is described herein with particular reference to dryers or dehydrators, it is understood that the invention is not limited thereto.

In mechanical refrigeration systems, for example, and in particular those operating with sulphur dioxide as a refrigerant, it is important to remove all traces of water vapor from the gas or from the refrigerating liquid as it leaves the compressor in order to prevent corrosion of the pipes through the refrigerator by moist fluid, and to prevent stoppage of action due to freezing of moisture. It has been the practice heretofore to employ moisture-absorbing materials such as silica gel for the purpose of removing the moisture from the gas.

It is, accordingly, an object of the invention to provide improved methods and apparatus for holding dehydrating material, such as silica gel, for example and assuring the passage of fluid to be treated through such material without carrying along any material.

It is an object to provide a dehydrator for holding the drying material with a single screen, and with inlet and outlet openings on the same side of the screen.

A further object is to form a baffle integral with a screen retainer.

Still another object is to render it easy to fill the receptacle with drying material and to secure the receptacle closed after it has been filled.

In carrying out the invention in accordance with a preferred form thereof, a deep drawn metal cup is provided having a relatively wide flange

2

around the rim at the top of the cup. A screen is provided for retaining the drying particles within the cup, and a screen retainer is provided which is adapted to fit between the screen and the rim at the top of the cup. The screen retainer has a baffle formed integrally therewith extending downwardly into the cup and diametrically along the screen. Preferably the retainer is secured to the screen. A head is provided having inlet and outlet openings, and having a rim with a flange adapted to fit around the rim of the screen and the screen retainer, with the flange fitting against the flange on the cup. The head is also provided with a bridge fitting against the top surface of the screen along a diameter thereof. The bridge and the baffle lie along the same diameter of the screen and fit against opposite sides of the screen.

A better understanding of the invention will be afforded by the following detailed description considered in conjunction with the accompanying drawing, in which

Fig. 1 is a vertical medial sectional view of the dehydrator forming one embodiment of the invention, together with apparatus for fabricating the apparatus as shown;

Fig. 2 is a bottom view of a screen retainer employed in the apparatus of Fig. 1;

Fig. 3 is a top view of a head for the apparatus shown in Fig. 1; and

Fig. 4 is a fragmentary enlarged sectional view of a portion of the apparatus of Fig. 1, illustrating the method by which the flanges of the head and the cup are united.

Like reference characters are utilized throughout the drawing to designate like parts.

The dehydrator shown by way of illustration, comprises a cup 11 containing a suitable granular or finely divided dehydrating material 12 such as silica gel, for example, with a screen 13 covering the cup 11 secured by a screen retainer 14, with a head 15 closing the cup 11, and securing the screen 13 and the screen retainer 14 in place. The cup 11 is preferably a deep-drawn cup composed of sheet steel or the like, having a relatively wide flange 16 around the rim 17 of the cup at the top thereof. Preferably the cross section of the cup 11 is circular. If a circular cup is employed, the screen 13 also has a circular outline, and the diameter thereof is sufficient so that the particles 12 of the drying material may be retained within the cup 11 by means of the screen 13.

For retaining the screen 13, the screen retainer 14 is preferably in the form of a flat ring, con-

forming in outer diameter to the outer diameter of the screen 13, having a rim portion 18 and having a diametrical cross portion or cross piece 19 integral with the rim portion 18. The screen 13 is composed of a non-corrosive substance such as Monel-metal wire, for example, which is relatively expensive. It will be observed that only one such screen is required.

For diverting the flow of fluid through the interior of the mass of the dehydrating material or particles 12, a baffle 21 is provided which is preferably integral with the cross portion 19 of the screen retainer 14. The screen 13 is preferably united or secured to the screen retainer 14 by some suitable fusion process such as brazing or soldering. In securing the screen 13 to the cross portion 19 of the screen retainer 14, the meshes or interstices of the screen 13 above the cross portion 19 are filled with the uniting material, such as solder or brazing material for the entire thickness of the screen.

The head 15 is formed with a circular rim 22, having a flange 23, with the same outer diameter as the cup flange 16 and adapted to be joined thereto. Preferably the flange 23 is offset from the rim 22 to form a groove 24 for holding the rim portions of the screen 13 and the screen retainer 14. The head 15 is dished or bowl-shaped with a bridge portion 25 depressed and lying along the same plane as the rim 22 so as to fit against the top surface of the screen 13. The bridge 25 extends diametrically across the head from one side of the rim 22 to the other, and the parts are so assembled that the diametrical bridge 25 of the head 15 lies along the diametrical cross piece 19 of the screen retainer 14. Inlet and outlet apertures or openings 26 and 27 are provided in the head 15 on either side of the diametrical bridge 25, and both openings are above the screen 13. As shown, suitable conduits or tubes 28 and 29 are provided for connection with the openings 26 and 27 respectively.

Before assembly with the other parts, the screen 13 and the screen retainer 14 are joined by filling in the interstices of the screen 13, where the screen 13 lies along the cross piece 19 of the screen retainer 14 and simultaneously uniting this portion of the screen with the cross member 19 of the screen retainer 14. This is preferably done by a fusion process such as brazing or soldering. Although not essential to the operation of the device, preferably several points around the periphery of the rim 18 of the screen retainer 14 are first united to corresponding points on the rim of the screen 13 to facilitate the operation of filling in the interstices of the screen 13 in a diametrical line or strip along the top of the cross member 19. If desired, the cross member 19 can also be united with the diametrical bridge 25 of the head 15 by soldering, brazing or the like—taking care to fill the interstices of the screen 13 to prevent flow of any fluid along the plane of the screen 13 between the bridge 25 and the cross portion 19 of the screen retainer 14.

The first operation before assembling the cup 11 with the remainder of the apparatus, is to fill the cup 11 to the top with the dehydrating material 12, whereupon the screen retainer 14 to which the screen 13 has been united is placed upon the top of the cup with the baffle 21 extending downward into the mass of material 12. The head 15 is then fitted to the top of the cup with the flanges 16 and 23 in abutment.

Preferably the rim 23 of the head 15 is welded to the rim 16 of the cup 11. To facilitate this

operation, preferably a bead 31 is formed around the lower surface of the head flange 23 and the two flanges are projection welded together. For this purpose a pair of annular welding electrodes 32 and 33 of a suitable material such as copper, for example, are provided and tungsten inserts 34 and 35, respectively, are provided which serve as heat-resistant shoes or contacts for the electrodes 32 and 33, and bear against the upper surface of the flange 23 and the lower surface of the flange 16, respectively. For receiving the insert 35, an annular recess 36 is formed in the lower electrode 33. Preferably a locating ring 37 of suitable heat withstanding electrical insulating material, such as mica 37, is provided for locating the flanges 16 and 23 preparatory to projecting welding.

A larger annular recess 38 is preferably provided for holding the locating ring 37. It will be understood that suitable means, not shown, are provided for supporting and moving the electrodes together as well as supplying electric welding current thereto. As a result of the combination of pressure between the welding head inserts 34 and 35 and the heat of the welding current, the bead 31 is fused and the adjacent surfaces 39 and 40 of the flanges 23 and 16 are brought into intimate contact and united as illustrated in Fig. 1.

When the device is placed in a mechanical refrigerator, for example, in the line between the compressor and the evaporator with refrigerating fluid entering through the tube 28 and leaving through the tube 29, the fluid follows the path of the arrows shown in Fig. 1 of the drawing. Since the space between the bridge 25 and the cross member 19 is filled by the material of the screen 13 and the brazing or soldering material filling the interstices of the screen, there is no passage-way of fluid except downward through the screen on one side and upward through the screen on the other side. The fluid is forced by the baffle 21 to travel through a considerable portion of the mass of the dehydrating material 12. Thus none of the fluid passing through the dehydrator is permitted to carry particles of water vapor as every portion of the fluid is brought into contact with the dehydrating material 12. The screen 13 prevents silica gel from being carried out into the fluid stream.

In accordance with the provisions of the patent statutes, we have described the principle of operation of a preferred embodiment of our invention together with the apparatus and desire to have it understood that the apparatus shown and described is only illustrative and that our invention may be carried out by other arrangements.

We claim:

1. A dehydrator comprising in combination a cup containing dehydrating material and having a flange around the rim of the cup, a head having inlet and outlet openings, a bridge extending diametrically of the head and lying along a plane substantially along the rim of said cup, and having flanges around the rim of the head conforming to the cup-flange, a screen, and a screen retainer, said retainer and screen having outlines conforming to the shape of the top of the cup, the retainer having a rim, a cross-piece, and a baffle formed integral with said cross piece and bent into a plane transverse to the plane of the retainer rim, said screen having said retainer cross-piece joined thereto by fusion process with joining metal filling the screen through the thickness thereof along said retainer cross piece, fitting

under the bridge of said head to close the screen to fluid passage over said retainer cross piece and under said bridge, said baffle extending downward into said dehydrating material and the flanges of said head and said cup being joined to secure said screen and retainer in position.

2. A dehydrator comprising in combination, a cup containing dehydrator material, a head over the top of said cup, a screen closing the top of said cup between said head and said cup, a baffle 10 extending into said cup from said screen, said head having a bridge contacting said screen along the line of said baffle, and means filling the interstices of said screen between said bridge and said baffle for deflecting flowing material from one 15 opening in said head through one side of said screen around said baffle through the dehydrator material in the cup through the other side of said screen and out through the second opening in the head.

3. A dehydrator assembly comprising in combination a cup having a rim, a screen extending across the rim of said cup, a baffle extending from one side of said screen into said cup, a head resting upon the other side of said screen with inlet 25

and outlet openings on said other side of the screen and with a bridge between said openings overlying said screen along said baffle, and means filling the interstices of the screen between the bridge and the baffle, said bridge, screen and baffle being in contact with one another whereby bypassing of said baffle is prevented.
